OR D 11.223

DESIGN FOR KNITTED FABRIC.

Design No. **11,223**, dated June 3, 1879

UNITED STATES PATENT OFFICE.

GABRIEL UPTON, OF PHILADELPHIA, PENNSYLVANIA, ASSIGNOR TO CONYERS BUTTON AND THEODORE A. FLEU, OF SAME PLACE.

DESIGN FOR KNITTED FABRIC.

Specification forming part of Design No. 11,223, dated June 3, 1879; application filed May 5, 1879.
[Term of patent 3½ years.]

To all whom it may concern:

Be it known that I, GABRIEL UPTON, of Philadelphia, Pennsylvania, have produced or invented a new and original Design for a Knitted Fabric, of which the following is a specification.

My design is fully shown in the accompanying photographic illustration.

The groundwork of the fabric is composed of loosely-knitted loops of light threads, and on this groundwork are arranged diagonal ribs *a*, formed of heavier threads, incorporated with the lighter threads of the groundwork. The diagonal ribs run in opposite directions and cross each other, so as to form diamond-shaped figures over the whole surface of the fabric.

Irrespective of the colors employed, I claim—
The design for a knitted fabric, said design comprising the loosely-knitted groundwork of light threads and the diagonal ribs of heavier threads, said diagonal ribs crossing each other, so as to form diamond-shaped openings, all substantially as described and shown.

In testimony whereof I have signed my name to this specification in the presence of two subscribing witnesses.

GABRIEL UPTON.

Witnesses:

WILLIAM J. COOPER,
HARRY SMITH.
